UNITED STATES PATENT OFFICE.

GEORGE EDWARD NYE AND EDWARD TREDICK, OF BRISTOL, PA.

DESIGN FOR A FRAME FOR KNITTING-MACHINES.

SPECIFICATION forming part of Design No. 15,474, dated October 21, 1884.

Application filed July 25, 1884. Term of patent 14 years.

To all whom it may concern:

Be it known that we, GEORGE E. NYE and EDWARD TREDICK, of Bristol, in the county of Bucks and State of Pennsylvania, have invented or produced a new and original Design 5 for Knitting-Machines, of which the following is a specification.

Our invention relates to a design for the frame of an upright rotary knitting-machine, 10 and particularly to the legs which sustain the bed of the machine, and to the "standards," so-called, which sustain the top plate.

Referring to the accompanying photographic illustration, A A represent the three legs, B 15 the bed-plate, C the standards or brackets, and D the top plate. Each leg has a gradual inward curvature as it rises from the foot to a point near its upper end, where it is turned suddenly inward beneath the bed-plate. The 20 legs are of increasing width toward their upper ends, and are beveled or chamfered on their outer edges, as shown at a. Near its upper end each leg has a flat inclined face, b, bearing in relief a monogram. There are two of 25 the standards C rising from opposite sides of

the bed-plate. In horizontal section they are curved to correspond with the form of the bed and top plates. Viewed from the outside they are contracted or diminished in width near the top and bottom. In its middle each plate 30 bears a large monogram. The panel is usually perforated or made of skeleton form, as shown, so that the monogram stands alone in the opening; but the characters may be arranged in relief on a solid ground or panel.

The leading features of the design are the legs and the standards in the form such as 35 represented.

What we claim as our design is—

The design for the frame of a knitting-machine, as herein shown and described.

In testimony whereof we hereunto set our hands, this 26th day of June, 1884, in the presence of two attesting witnesses.

GEORGE EDWARD NYE.
EDWARD TREDICK.
